(57) **CLAIM**

The ornamental design for a blow-molded rib structure for a table, as shown and described.

DESCRIPTION

FIG. 1 is a perspective view of a blow-molded rib structure for a table according to my new design;

FIG. 2 is a perspective view of a lower component of the blow-molded rib structure of FIG. 1, viewed from the same direction as FIG. 1 and enlarged for clarity of illustration; and,

FIG. 3 is a perspective view of the lower component of the blow-molded rib structure of FIG. 1, viewed from a different direction and enlarged for clarity of illustration.

The broken lines showing a table illustrate environment and form no part of the claimed design.

1 Claim, 3 Drawing Sheets

FIG. 1

FIG. 2

FIG. 3
